BURNER CONTROL MECHANISM

George D. Bower, University City, Mo., assignor
to Automatic Control Corporation, St. Louis,
Mo., a corporation of Delaware

Application January 27, 1941, Serial No. 376,127

38 Claims. (Cl. 158—28)

The present invention relates to a control mechanism for controlling a heat responsive device, and particularly a burner.

The mechanism includes generally a control motor operable at a given rate, a pair of relays and a plurality of cam switches operated by the motor. The several switches control, with the relays, circuits for the control motor, a burner motor or like device, an ignition device, and a fuel valve or like device.

The switches are arranged to provide a cycle, and they include a space or room thermostat with an instituting circuit, whereby the heat-change device is set into operation in response to operation of the thermostat. The cycle includes a starting phase, a running phase, a scavenging phase, and a lock-out phase adapted to operate upon failure of the starting phase to constitute operation of the heat-change device.

In the starting phase, the mechanism is first under direct control of the room thermostat through the instituting circuit, and is designed to operate through a predetermined cycle if the thermostat remains closed a brief interval sufficient to get the cycle under way by establishing holding circuits shunting the instituting circuit. Thereafter, the complete starting cycle will be performed, regardless of displacement of the room thermostat, at the end of which the mechanism returns to control of the room thermostat for a running period. During the running period the control motor is inactive, but upon satisfying of the room thermostat, the mechanism may take up where it left off, at the end of the starting cycle, complete a closing or scavenging cycle, and be ready for a subsequent operation.

In the starting cycle the burner motor and control motor first begin, followed by the ignition device, and the oil supply device, with an added oil pre-heating control interposed.

If the starting cycle fails to cause proper operation, the lock-out circuit will operate, but only after an intervening scavenging period; and the mechanism will move to a position requiring manual reset for further operation.

If the power fails at the outset of the starting cycle, while the instituting circuit is closed, there will be merely an interruption thereof. If it fails after the starting cycle holding circuit is established, upon restoration of power the mechanism will run through the interval of a complete cycle including scavenging without the fuel line open, and reinstitute the starting phase, dependent upon the condition of the room thermostat when the mechanism attains the new start-

ing position. If power fails during the running period, upon return of power the mechanism will complete a scavenging period and reinstitute a starting cycle, again dependent upon the then condition of the room thermostat. If power fails during a scavenging period, upon return of power, it will complete the scavenging period.

If ignition fails during the starting phase, the results are as above. If ignition, or flame, fails during a running period, as by breaking of the fuel supply, the mechanism will then complete a scavenging period, by restart of the control motor, at the end of which it may reinstitute a starting cycle. If the failure was due merely to an extinguishing of the flame or other temporary dislocation, the starting cycle may reestablish operation. If, however, the failure is not remedied, ignition will not take place during the new starting cycle and the lock-out cycle will operate, requiring manual reset.

Thus, toward the end of the scavenging period, at the point where the lock-out operation may be effected, the continuance of the operation into lock-out or to recycling will depend upon the conditions at the end of the starting period. If these conditions consisted of a failure to ignite at the end of an ignition or starting period, the lock-out mechanism will operate. Under all other conditions, the lock-out mechanism will not operate, and the mechanism will reinstitute a new starting cycle and automatically determine whether the failure has been corrected or can be corrected by re-ignition.

The objects of the invention are to obtain each of the above functions, severally or in combination. It is a further object to accomplish the same in a relatively simple mechanism.

It is a further object to provide a manual reset device that is operated by movement to establish its circuits, but which is ineffective to alter any circuits after it has been moved, so that holding it in operating condition has no effect. More particularly, it is an object to provide a reset mechanism giving a limited displacement of the control motor cams to reset the mechanism in a desired position, wherefrom it automatically operates.

Additional objects will appear from the description to follow, with especial reference to the explanations of the operations produced by the mechanism, whether they be normal or abnormal cycles.

This application is related to Serial Number 366,512, filed November 22, 1940, by this applicant.

In the drawings:

Figs. 16 to 39, inclusive, are wiring diagrams of the mechanism in its various operations;

Fig. 40 is a general wiring diagram; and

Fig. 41 is a modified wiring connection.

Referring to Fig. 1, there is shown a box 40 containing the switch constructions and control. In the rear of this there extends a stack element 41 secured to and projecting into a stack pipe 42, or the like, this pipe representing some element of a burner device that is rapidly subject to the heat changes of the burner itself. Details of the unit 41 are disclosed in copending application Serial No. 366,512, filed November 22, 1940, by this applicant, and in Patent No. 2,323,370, issued July 6, 1943, to this applicant.

Stack switch unit

In general, the unit consists of two tubes, one within the other and so designed that upon a quick reversal in the temperature of the gases applied to the outer tube, there will be an inward or outward displacement of the inner end of the inner tube so as to actuate a switch, although upon further change of heat without a reversal, or even upon normal modulations of the burner flame occurring at relatively slow rates, both tubes may change in length without additionally shifting the switch.

As set forth in said copending application, at the start with the burner at room temperature, the tubes have a starting length differential. In this condition, the switch lever may occupy a medial position between its two extreme positions to either of which it is urged by its snap-action means. In this position of the tubes, the resiliency of the switch members will permit the switch blade to be moved to either extreme, coming under the influence of the snap-action means, and it will remain where so placed because the action of the tubes is not sufficient to overcome the force of the snap-action.

When unlimited heat is suddenly applied to the outer tube rapidly, it will expand, but the

inner tube cannot expand so rapidly, owing to the fact that the inner tube is connected to a "cold reservoir" into which it constantly may discharge heat, and also to the fact that the inner tube is shielded in a major portion by the outer from the applied heat. So long as the heat is applied to the outer tube, at a rate greater than that to which it flows to and out of the inner, there will be a plus length differential that will actuate the switch. When the burner ignites, this plus differential will be attained quickly (preferably in only a few seconds), and the switch will be operated.

Thereafter, upon continuation of heat from the burner, the inner tube may receive more heat. However, as it is constantly dissipating heat into the cold reservoir, it should never reach the starting length differential. Even if it did, it would not shift the switch because at the starting differential the difference in length is not sufficient to overcome the snap-action force.

During operation there may be modulations downward of the burner. The rate of heat input into the outer tube is so much greater than the rate of heat absorption by the inner that these modulations all occur way above the rate change required to operate the switch. Hence, the switch will not be made to respond to such modulations.

When the burner stops, however, the rate of heat input into the outer tube drops to a very small amount (if any), less than that critical one at which the heat into the outer tube substantially equals the rate of heat absorption by the inner. Thereupon, the outer tube will quickly contract. The inner tube cannot dissipate its heat so rapidly, and the length differential becomes minus, causing the switch to return to its starting position. Subsequent cooling to a temperature providing starting length differential cannot reshift the switch, for reasons already described.

In these operations, particular temperature values do not mean anything. The unit will operate from any starting temperature, and will return upon stopping of the flame from any running temperature. It is not dependent upon a predetermined temperature differential. It depends upon rate of heat change so that it will not operate even upon wide modulations at normal rates. Its rate of change value for operation, however, is constantly small, so that it will operate quickly upon rapid reversal of applied temperature from any precedent temperature, low or high.

The casing 40 includes a back wall 44, a top wall 45 and a bottom wall 46; and it also includes side walls 47 and 48 that do not extend as far forward as do the top and bottom walls. Across the front ends of the side walls is secured a partition wall 49. On the back wall 44 is mounted a snap-action switch 50 having terminals 51 and 52, contact between which is made or broken by the stack unit 41, all as described in the said copending application.

Control motor and relays

Secured to the back side of the partition wall are 70 a clock or control motor 54, a first relay 55 and a second relay 56. Projecting through the partition wall 49 is a cam shaft 57 on which are mounted a plurality of cams. Likewise, projecting through the partition wall 49 are a plurality of terminals 58 to 67, inclusive. Secured to the

front of the partition wall are a plurality of cam switches, to be described.

The control motor 54 is attached to a plate or bracket 70 that is spaced somewhat from the partition wall, but is secured thereto. This plate nonrotatably supports a reset shaft 71 having at the end thereof a knob 72 that may rotate a limited distance, as will be described. This knob has a leaf spring 73 projecting from the back face thereof and adapted at times to register with a button 74 on the front cam. When the button drops in front of the edge of the leaf spring 73 the knob 72 may be turned counterclockwise a sufficient distance to displace the front cam and the remaining cams with it an angular distance adequate for resetting of the device, as will be described.

There are three cams 76, 77, and 78 secured in spaced relation and nonrotatably mounted on the cam shaft 57. The cam shaft, in turn, rotates on the reset shaft 71. At its rear end between the partition wall 49 and the plate 70 it has formed on it a ratchet wheel 79. This ratchet wheel is engaged by a ratchet dog 80 (Figs. 4 and 5), spring urged into contact, and pivotally mounted on a gear 81 set within an opening in the partition wall and rotatably on the cam shaft. A guard sheet 82 is also mounted on the cam shaft to protect the gear 81 and to cover the opening.

The gear 81 meshes with the pinion 83 that is rotated by the control motor 54. Rotation of the pinion 83 in forward direction causes rotation of the gear 81 and correspondingly rotation of the ratchet wheel 79 through the ratchet dog 80 and with it the cams. The ratchet permits rotation of the cams in the forward direction, independently of the gears and motor.

Cam switches

There are three banks of cam switches, each bank being operated by one of the cams. All of these switches are mounted between the brackets 84 and 85 secured to the front of the partition wall 49. Suitable blocks of insulation separate the several switches and each has its switch blades projecting back of the blocks to provide terminal posts.

The front cam 76 (Fig. 8) has an edge 87, a lower edge 88, a notch 89 and a lobe 90. There are three switches actuated by this cam. They are generally indicated at 91, 92, and 93. There is a cam follower arm 94 having a contact 95 cooperating with an additional contact 96 on a spring arm 97 to form the switch 91. A suitable stop blade 98 limits the movement of the spring arm 97 toward the cam.

A spacer member 99 secured between the spring arm 97 and another spring arm 100 will cause them to move together. The spring arm 100 has a first contact 101 adapted to engage with a contact 102 on a spring blade 103 to form the switch 92. A stop blade 104 limits the movement of the spring arm 103 in its movement away from the cam.

The spring arm 100 has an additional contact 105 adapted to engage with contact 106 on a spring arm 107 to form the switch 93. The spring arm 107 is limited in its movement toward the cam by a stop blade 108.

In the position shown in Fig. 8, the cam follower 94 is in the notch 89 so that the switch 91 is open, the switch 92 is closed, and the switch 93 is open. As the cam rotates counterclockwise, the follower arm 94 will be lifted first to close the

switch 91. Thereafter, it will ride onto the lobe 90 to produce a maximum displacement in which the switch 93 first closes, and then the switch 92 opens. Subsequently, the follower falls to the edge 87 in which the switch 92 closes, the switches 91 and 93 remaining closed. When the follower 94 subsequently falls to the edge 88, the switch 93 will open, the other two remaining closed.

The middle cam 77 (Fig. 9) has an outer edge 110 followed by a deep notch 111, after which occurs a low edge 112 followed by another deep notch 113. The notch 113 is followed by an edge 114 corresponding to the edge 112 which, in turn, is followed by a medium edge 115 which terminates in the edge 110. This cam operates switches 117, 118 and 119.

It has a cam follower 120 having on it a contact 121 adapted to engage with the contact 122 on a spring blade 123 to form the switch 117. A stop blade 124 limits the movement of the spring blade 123 toward the cam.

The blade 123 has an additional contact 126 adapted to close with a contact 127 on a spring blade 128 to form the switch 118. A stop blade 129 limits the movement of the blade 128 toward the cam. A spacer member 130 is disposed between the blade 128 and a spring blade 131 to cause them to move together. The blade 131 has a contact 132 adapted to register with the contact 133 on a spring blade 134 to form the switch 119. A stop member 135 limits the movement of the blade 134 toward the cam.

When the follower 120 is within the deep notch 113 all of the switches are open. When the cam rotates counterclockwise lifting the follower 120 into the edge 114, this closes the switch 117. Thereafter, when the follower rides onto the higher edge 115, it closes the switch 118. Subsequently, when it rides onto the high edge 110, it closes the switch 119 so that all of the switches will close. Thereafter, when the follower drops into the deep notch 111 all three switches open. Subsequently the edge 112 will lift the cam follower 120 to close the switch 117 which remains closed until it is opened by the arm 120's dropping into the deep notch 113.

The rear cam 78 (Fig. 10) has a lobe 140 followed by a low edge 141 terminating in a notch 142. The notch is followed by a low edge 143 corresponding to the edge 141; and the edge 143 is followed by a high edge 144 which extends to the lobe 140. This cam operates four switches, 145, 146, 147 and 148.

There is a cam follower arm 150 having a contact 151 adapted to engage with a contact 152 on a spring blade 153 to form the switch 145. A stop blade 154 limits movement of the blade 153 away from the cam.

The follower arm 150 has a spacer member 156 connecting it to the spring blade 157 so that they move together. The spring blade 157 has a contact 158 adapted to engage with the contact 159 to form the switch 146. The contact 159 is mounted upon a spring blade 160, movement of which toward the cam is limited by a stop blade 161.

A spacer member 162 is secured between the blade 160 and a spring blade 163, having a contact 164. This contact is adapted to engage with a contact 165 on a spring blade 166 to form the switch 147. A stop blade 167 limits movement of the spring blade 166 toward the cam.

The spring blade 166 supports an additional contact 168 adapted to engage with a contact 169 on a spring blade 170 to form the switch 148.

A stop blade 171 limits movement of the blade 170 toward the cam.

With the follower 150 on the edge 141, as shown, switches 145, 147 and 148 will open and the switch 146 is closed. When the follower drops into the notch 142, the switch 148 opens and the switch 146 closes. Thereafter, when the follower rides onto the edge 143 the switch 145 is again opened, and the switch 146 closes. Subsequently, when the cam follower rides on the edge 144 it additionally closes the switch 141. Subsequently, when the lobe 140 lifts the follower arm 150 it further closes the switch 148. Thereafter, the follower drops to the edge 141 opening the switches 147 and 148, but keeping the switch 146 closed.

External mechanisms and connections

The mechanism is adapted for use with a room thermostat, an oil supply device such as a solenoid valve in the oil line, an ignition producing device and a burner device such as a blower motor, or the like. Two of the terminals, such as 59 and 60, are connected to the room thermostat, two others, such as 61 and 62, are the two power line terminals. One of the terminals, such as 63, is connected to one lead from the oil supply valve, the other lead from which is connected to the other power line, such as by way of the terminal 62. Another terminal, such as 64, is connected to the ignition device, the other lead from which is brought from the power line such as by way of the terminal 62. Another terminal, such as the one 65, receives one lead from the burner motor, the other lead from which is carried to the power line as by way of the terminal 62. The two remaining terminals such as 66 and 67 are connected to an additional control, such as an oil pre-heating means.

The particular arrangement of the terminals is not important provided the connections are in accord with the wiring diagram. In Fig. 40, one power line terminal is shown at 61 and the other at 62.

Internal connections

The relay 55 and the relay 66 are similar. The relay 55 has a coil 180 operating on one double-acting armature 181, which is closed with the contact 182 when the coil 180 is deenergized. Upon energization of the coil, the armature 181 moves against a contact 183. The coil 180 likewise moves an armature 184 against a contact 185 upon energization.

The relay 66 has a coil 186 that, when energized, opens a switch 187 and closes a switch 188. It also opens a switch 189 when energized. When not energized, the coil 186 releases the switches 187 and 189 into closed position.

One terminal of the switch 145 leads to the power line 61. The other terminal is connected with the switch 187, with the switch 148 and one terminal 59 of the room thermostat. The other terminal 60 of the room thermostat is connected with one terminal of the switch 50, with the relay coil 180, and with the switch 117. The other end of the coil 180 leads to the other terminal 62 and thence to the power line. The other lead from the coil 186 extends to the terminal 62.

The armature switch blade 181 is connected with the power line terminal 61.

The contact 183 of the first relay is connected with one side of the switch 81 and also with one side of the switch 184 operated by the first relay coil 180. The other side of the switch 184 is connected with one side of each of the switches

118, 187, 188 and 117. The other side of the switch 119 is also connected with one side of each of the switches 188, 148, and 147. The other side of the switch 147 is connected to the terminal 63 leading to the oil supply mechanism and thence with the other power line, as at 62.

The contact 182 of the relay switch 181 is connected with one side of the switch 146, the other side of which is, in turn, connected with the other side of the switch 91, with the burner motor terminal 65, and also with one side of each of the switches 189 and 119. The other sides of each of the switches 189 and 119 are likewise connected together and to one side of each of the switches 92 and 93, and to the terminal 66 for the oil pre-heating mechanism. The switch 93 leads to the ignition mechanism terminal 64 and thence to the terminal 62. The switch 92 is connected at its other side with the other terminal 61 of the pre-heating mechanism, and with the control motor which, in turn, is connected to the terminal 62.

The manual reset

The reset knob 72, as shown in Figs. 11-14, has an axial opening therein by which it fits rotatably over the shaft 71. This opening enlarges into a chamber receiving the operating mechanism.

Within the chamber there is a flanged disc 190 having a notch 191 (Fig. 12) in one edge thereof. A torsion spring 192 is anchored at one end in the disc 190, and at the other end in a second flanged disc 193 at the bottom of the chamber. The second disc is nonrotatably mounted on the shaft 71 by fitting over a flat 194 thereon. The flange of the second disc 193 is cut away as at 195 for a certain arcuate distance.

A key 197 is secured parallel to the axis to a wall of the chamber by a screw 198. This key engages with low tolerance in the notch 191 of the disc 190, and engages also in the larger notch 195 of the second disc 193.

An expander segmental ring 199 engages in a groove in the knob to hold the upper disc in place in the chamber. A second contractile spring 200 engages around the shaft outside of the disc 190 to hold the knob assembly on the shaft.

The shaft 71 is nonrotatably mounted on the partition. The knob may be turned counterclockwise on the shaft. In this, the key 197 carries the disc 190 while the shaft holds the disc 193, causing the normal clockwise torsion of the spring 192 to be increased. The key moves in the notch 195 until it strikes the counterclockwise end thereof, whereupon further movement is prevented. Upon release of the knob, the spring returns it to its first position.

A cap 201 closes the chamber.

Additional connections

As shown in Fig. 40, a limit switch L may be inserted between the lead from the switch 185 and the switches 183 and 91. This location has advantages to be pointed out. A limit switch may be located in one power line, as at L2, which will have results to be pointed out.

As shown in Fig. 41, a slight change in the connections avoids even the potential hazard of carelessly connecting the igniter to the oil valve terminal 63 and the oil valve to the terminal 64. Such misconnection in the circuit of Fig. 40 would result in supplying oil prior to operation of the igniter.

In Fig. 41, the terminal 84 is not connected with the control motor circuit, but is connected by two parallel circuits with the terminal 63. These circuits include two switches 93 and 203. The switch 93 provides intermittent ignition controlled as shown in the diagram of Fig. 15. The switch 203 is a screw contact switch that, when turned down, shunts the switch 93 for constant ignition, and when turned up, leaves control under the intermittent switch 93.

OPERATION

At the start (Fig. 40) the switches 145, 91, and 92 are the only cam switches closed (see Fig. 15). This is a position represented by rotation of the cams, as shown in Figs. 8, 9, and 10, a short distance counterclockwise, the distance being such as to cause the follower arm 84 (Fig. 8) to ride out of the notch 89 into the short edge immediately preceding the lobe 80; to cause the follower 120 (Fig. 9) to be in more or less the middle of the notch 113, and to drop the follower arm 150 (Fig. 10) into the notch 142. At this time, the stack switch 50 is cold and hence open, as a consequence of which the coil 186 is deenergized, the switches 187 and 189 are closed, and the switch 188 is opened. The coil 180 is deenergized owing to the fact that the room thermostat T is open and the switch 117 is open. With this coil deenergized, the switch 181 is closed against the contact 182 and the switch 184 is open.

Normal cycling: Starting

If the room thermostat closes demanding heat, an instituting circuit is established, as shown in Fig. 16. This circuit extends from the terminal 61 through switch 145, the room thermostat T, and the coil 180 to the terminal 62. The results from energizing the coil 180 are shown in Fig. 17. The coil closes the switch 181 against the terminal 183 (designated switch 193) and also closes the switch 184. This immediately shunts the instituting circuit through the switch 145 by a circuit from the terminal 61, through the switch 181, the switch 184, and the switch 187 to the room thermostat, although this alternative circuit is immaterial. This circuit depends upon power in the lines and upon a cold stack. There is also established a circuit to the control motor through the switch 183, switch 91, and switch 189 (dependent upon a cold stack), switch 92 and the control motor to the terminal 62. There is further established a similar circuit to the burner motor as is clear from Fig. 17. These two devices then begin to operate, the burner motor without fuel.

After the lapse of about 3 seconds, as shown in Fig. 18, the switches 117 and 93 close. The previous circuits remain as described. Closing of the switch 117, however, shunts out the room thermostat and the stack switch as controls for the coil 180 by establishing a starting cycle holding circuit from the terminal 61, switch 183, switch 184, switch 117 and the coil 180 to the terminal 62. The coil 180 is thereafter held in circuit as long as power continues, independently of the instituting circuit through the switch 145 and the thermostat, but dependent upon continuous power because of the power failure relay switch 184. Closing of the switch 93 puts the ignition device in circuit in parallel with the control motor and the switch 92. Ignition, however, does not take place because the oil supply means or valve is not in operation.

After the lapse of 5 seconds, the cycle changes if the oil is not heated, as represented in Fig. 19. At this time, the coil 180 remains energized through its three different circuits. The ignition mechanism continues in operation as before, but the switch 92 opens. An alternate circuit around the switch 92 is provided through the oil pre-heating control mechanism A. If the oil is cold, the pre-heating mechanism opens this alternate circuit and the control motor stops. The ignition mechanism and the burner motor continue in circuit until the oil is heated and the alternate circuit through the pre-heating mechanism is closed by the mechanism A. Hence, the cycle remains static for this interval if the oil is cold.

The condition when the oil is adequately heated at the 5 second point is represented in Fig. 20. In it, the circuits established as shown in Fig. 19, remain but the mechanism A again closes the circuit to the control motor through the alternate circuit shunting the switch 92. The control motor then again operates to continue the cycle. It will be clear that if the oil is hot the control will not stop upon opening of the switch 92.

After the lapse of 10 seconds (Fig. 21), (omitting whatever intermission may have occurred because of cold oil), the switch 145 opens and the switches 146, 118, and 92 close. Opening of the switch 145 opens the instituting circuit, which remains open until the beginning of a new cycle, to prevent fortuitous reenergization of the coils 180 or 186 once deenergized, and leaves the coil 180 dependent upon its two circuits through its own switches 181 and 184, one of which circuits includes the switch 187 and the room thermostat, the other of which includes the switch 117. Closing of the switch 118 has no immediate effect. Reclosing of the switch 92 shunts out the oil temperature control mechanism and holds the control motor circuit independently thereof. Closing of the switch 146 cocks a scavenging circuit, but has no immediate effect since the switch 181 is not closed with the contact 182. It will be forecast, however, that the scavenging circuit and the instituting circuit cannot both be energized at once, since the switches 145 and 146 cannot be simultaneously closed. Upon power failure during the closure of the instituting circuit, there will be no following scavenging operation commencing upon restoration of power, as will be explained.

After the lapse of 20 seconds, as shown in Fig. 22, the switch 119 closes. This produces no immediate change, but provides a circuit for the control motor and ignition mechanism independently of the switch 188 and, hence, independently of the stack switch 50 that controls the coil 186. Whereas hitherto the control motor operation has been dependent upon lack of ignition, it may be held in circuit upon closure of this switch 119, even though ignition occurs.

After the lapse of 30 seconds, as shown in Fig. 23, the switch 147 closes. The other circuits to the igniter, the control motor, and the burner motor remain as in Fig. 22. However, the oil supply control is energized through the now closed switch 147, the circuit being switch 183, switch 184, switch 118, switch 147, the oil control to the other power line. This oil control may be a solenoid valve, or the like, through which oil is supplied to the burner. Ignition may thereafter occur.

When ignition occurs, the circuit changes as

shown in Fig. 24. Ignition almost instantly produces a shifting of the stack switch 50 to closed position. This puts the second relay coil 186 in circuit in parallel with the coil 180. Upon energization of the coil 186, the switch 187 opens, the switch 188 is closed and the switch 189 opens.

Opening the switch 187 breaks the circuit to the two coils 180 and 186 through the room thermostat. However, the coils remain energized through the switch 117. Closing the switch 188 establishes an alternate circuit to the oil supply mechanism in parallel with the switch 118, this circuit being dependent upon continued ignition. Opening the switch 189 leaves the circuit to the igniter and to the control motor dependent upon the switch 119.

After the lapse of 115 seconds, as shown in Fig. 25, the switch 148 closes. This is the running period holding switch for the coils 180 and 186, and provides an additional circuit for the coils 180 and 186 as follows: switch 183, switch 184, switch 188, switch 148, the room thermostat, through both of the coils to the other terminal. It will be seen that this circuit is dependent upon continuation of combustion to hold the switch 50 closed and, in turn, to hold the switch 188 closed. It likewise puts the two coils back into dependence upon the room thermostat. It will be observed that all of these circuits through the switch 188 are dependent upon continuation of power, because they are dependent upon the holding circuit through the switch 184 which opens upon failure of power. The mechanism is thus cocked for the running period, since it is in position to be made dependent upon the room thermostat.

Running period

After the lapse of 120 seconds, as shown in Fig. 26, the switches 117, 118, 119, and 83 open. Opening of the switch 117 leaves the coils 180 and 186 dependent upon the room thermostat circuit. Opening of the switch 118 leaves the coils and the oil supply mechanism dependent upon the circuit through the switch 188 which, in turn, is dependent upon continued power and combustion.

Opening the switch 119 breaks the circuits to the ignition device and the control motor, because the switch 189 is already open. Opening the switch 83 cuts the ignition device out of circuit, regardless of the control motor. The burner motor continues to operate.

This is the running period. At this time, the circuits are dependent upon continued combustion and continued power, which will be explained. They are also dependent upon the condition of the room thermostat. The control motor is inoperative, so that the cycle stops until the room thermostat opens or until flame failure, or power failure.

Scavenging period

At the instant the room thermostat is satisfied and opens, the circuit becomes as shown in Fig. 27. It will be remembered that in the running period the only circuits to the two coils are through the room thermostat. At the instant of opening of the thermostat, the switch 50 will be closed because the heat of combustion is still present. However, the coil 180 is instantly deenergized shifting the switch 181 against the contact 182 and opening the switch 184. Shifting of the switch 181 to the contact 182 (known as switch 182) closes the circuit through the switch 148 and holds the burner motor in circuit. However, the oil supply is cut off and flame will stop.

Deenergization of the coil 186 causes the switches 187 and 189 to close and the switch 188 to open. This operation of the switches 187 and 188 has no effect, their circuits being otherwise broken. Closing the switch 189, however, reestablishes the circuit to the control motor through the switch 182, switch 148, switch 189, switch 92 to the control motor, this circuit being designated as the scavenging circuit. It will be remembered that the switch 83 is opened at the beginning of the running period, so that the ignition mechanism is not in circuit. The burner motor is in circuit to purge the furnace and connections of residual fuel. A very short time after stopping of the flame, as shown in Fig. 28, the stack unit cools, opening the switch 50, with no additional effect.

After 123 seconds, as shown in Fig. 29, the switch 117 recloses. This has no effect on the cycle at this point. The three second gap for the running period in operation of the switch 117 is adequate to accommodate coasting of the control motor after its deenergization without reclosing the switch 117.

Thereafter, after 125 seconds, the switches 147 and 148 open as shown in Fig. 30. These have no effect on the normal cycle but had to be closed throughout the running period. After 175 seconds, as shown in Fig. 31, the lock-out switch 91 opens. This has no effect on the normal cycle. After about 178 seconds, as shown in Fig. 32, the switch 117 reopens. This has no effect on the normal cycle. After about 181 seconds, as shown in Fig. 33, the switch 81 recloses. This has no effect on the normal cycle.

After about 185.5 seconds, as shown in Fig. 34, the switch 148 opens and the switch 146 recloses. This is the starting position as closing the switch 145 reestablishes the instituting circuit to the coil 180 dependent upon the room thermostat, and opening the switch 146 breaks all circuits to the control motor and the burner motor.

Lock-out

It will be seen from the foregoing that there is a starting period, a running period, and a scavenging period. It will now be shown how the lock-out mechanism operates.

Fig. 24 discloses the condition at the time ignition takes place and Fig. 25 shows the arrangement with ignition after expiration of 115 seconds.

The absence of ignition at 115 seconds is shown in Fig. 35. The switch 188 closes to establish the circuit through the room thermostat to the coil 180 and also to establish an alternate circuit to the oil supply device, but the failure of the switch 50 to close prevents energization of the coil 186, as a consequence of which the switch 187 and the switch 189 remain closed and the switch 188 remains open. It will be seen that the circuits are cocked at this time for holding both the coil 180 and the control motor upon the subsequent opening of the switches 117, 118, and 119. Likewise, the fact that the switch 188 remains open predicts the condition of the oil supply upon opening of the switch 118.

With no ignition, the conditions at 120 seconds are shown in Fig. 36, which is the normal point for starting the running period. The switches 117, 118, 119, and 83 open. The coil 180 is held in circuit through the switch 183, the switch 184, the switch 187 and the room thermostat. The oil supply remains in circuit, by being put across the room thermostat and the coil 180 through the switches 148 and 147. The control motor re-

mains in circuit through the switch 189 although the parallel switch 119 opens. Opening of the switch 93 disconnects the igniter and the burner motor remains in circuit.

After 123 seconds, with no ignition, as shown in Fig. 37, the switch 117 recloses reestablishing a holding circuit of the coil 180 independent of the room thermostat. The other circuits remain unchanged.

After 125 seconds, with no ignition, as shown in Fig. 38, the switches 147 and 148 open. Opening these switches breaks the circuits to the oil supply. The remaining circuits are not changed.

After 175 seconds, with no ignition, as shown in Fig. 39, the switch 91 opens. This breaks the circuits to the control motor and to the burner motor. The cycle, therefore, stops with the coil 180 held energized. Manual reset is required to reestablish the circuits.

Manual reset

This manual reset is accomplished by rotating the knob 72 counterclockwise as far as it will go. The mechanism, as shown in Figs. 1-10, is in the lock-out position. The button 74 on the front cam 76 has just passed under the leaf spring 73 and is immediately in front thereof. Hence, rotation of the knob displaces the cams counterclockwise under the ratchet an angular maximum distance just sufficient to return the control motor switches to starting position. Release of the knob permits it to return to its original position under the influence of its spring. Further cycling will then depend upon the condition of the room thermostat.

It may be noted that if the manual reset is operated only partially to starting position, so as to reclose the switch 91, the switch 117 will be opened, causing the relay switch 183 to break and 182 to make, and establishing the scavenging circuit to return the mechanism to starting position. The switch 117 must break not later than opening of the switch 148, as otherwise the switch 148 will not determine the starting position. On the other hand, the switch 117 must hold beyond the lock-out opening of the switch 91, in order to hold the switch 183 away from the scavenging circuit.

Fortuitous shift of the room thermostat

There are only two periods in which fortuitous action of the room thermostat can have any effect. These periods are at the start and at the interval between 120 and 123 seconds, which is normally the running period, but which may come during a prelude to a lock-out.

If the room thermostat opens prior to the closure of the switch 117, the mechanism will stop but will be fully prepared to start again when the thermostat recloses, and will continue the cycle. Of course, after the switch 117 is closed, it is immaterial whether or not the room thermostat changes its position. If the thermostat, however, is open at the beginning of the running period, the result will be merely a completion of the cycle through the scavenging period and the return to the start. If the room thermostat opens and then recloses during the running period, the mechanism will nevertheless, upon opening, cycle through the scavenging period and return to the start, because the moment the thermostat opens the switch 184 opens. If the room thermostat opens during the interval otherwise devoted to the normal running period, represented in Fig. 35, but where there has been no igni-

tion, the coil 180 will be cut out of circuit, opening the switch 184 and shifting the switch 181 into contact with the contact 182. This will then institute the scavenging cycle represented by Figs. 28-34 inclusive, so that the mechanism returns to its starting position and will automatically recycle again upon demand by the thermostat.

It will be observed that during the lock-out period, the switch 117 is closed, holding the coil 180 independently of the thermostat.

Flame failure

If the flame fails during the running period, as shown in Fig. 26, the switch 50 will open deenergizing the coil 186. This will close the switch 187 and open the switch 188. This will be an adequate break to release the coil 180 with the resultant opening of the switch 184 and shifting of the switch 181 to the contact 182. When this occurs, the result is the same as opening of the room thermostat, and the mechanism cycles out its scavenging period and returns to its start.

Power failure

Power failure at any time immediately releases the two coils. If this failure occurs during the first 10 seconds when the switch 145 is closed, restoration of power will merely re-institute the cycle because the coil will be reenergized through the switch 145.

If power fails thereafter, as shown in Fig. 21, the coil 180 will release the switch 184 to open so that the coil 180 is not subject to reenergizing. However, by this time the switch 146 is closed so that the switch 181, upon shifting to the contact 182, establishes circuits to the control motor and to the burner motor and to the igniter which may function as in a normal starting cycle, but without oil. When the cycle reaches the running period, after 120 seconds, it passes directly across the running period and continues with the scavenging period, ultimately returning to the start. In this, it is immaterial whether or not any ignition has occurred, as by residual oil, as the two coils 180 and 188 cannot be energized. Note that by closing the switch 146 at the time switch 145 opens, a scavenging period is assured after any flame or power failure when the instituting circuit is open, whereas power failure prior to opening of switch 145 is automatically remedied upon restoration of power.

If there is power failure during the running period, the effect is the same as if the room thermostat were to open. Upon restoration of power, the mechanism cycles through the scavenging period and then restarts.

Upon power failure and restoration during the scavenging period, the mechanism starts where it left off before failure.

It will be seen that, after every possible cycle, whether normal or after power failure or after flame failure, there is a scavenging period insuring the complete discharge of all unconsumed fuel.

Likewise, it may be observed that, although the lockout does not come until the end of the scavenging period, whether it will occur is predetermined at the end of the starting period. In other words, whether or not the mechanism will operate into the lock-out position after 175 seconds or whether it will return to the starting position after 175 seconds is predetermined at the end of 120 seconds, and lock-out follows only a failure of ignition at the beginning of the running period.

Other abnormal operations

If the switch 50 sticks in open position, a lock-out will result, as the result is the same as a failure of ignition. If the switch 50 sticks in hot position and fails to open, at the end of a running period the mechanism will nevertheless cycle out its scavenging period because the relays are otherwise deenergized. However, recycling cannot take place thereafter, as the relay 186 will be energized immediately upon establishing the instituting circuit, causing the switch 189 to open and, since the switch 119 is open at the start, the control motor cannot start. Under this condition, the burner motor will operate without ignition or oil.

Likewise, if the relay 186 sticks in hot position during a running period, at the end of the running the control motor cannot restart owing to its dependency at that time upon the switch 189. Hence, the burner motor will operate without oil. Lock-out will follow its sticking in cold position.

If the relay switch 180 sticks in open position, no start can occur, because the control motor circuit is dependent upon its assuming its closed position. If it sticks in closed position during a running period, upon opening of the thermostat the scavenging circuit cannot be instituted, as it depends upon the switch blade 181 in open position against contact 182. But breaking of the room thermostat will deenergize the coil 186, opening the switches 188 and 189 and closing the switch 187. The oil valve circuit will then be closed through switches 183, 184, 187, 188 and 147. But the control motor will again start, upon closing of the switch 189, with the result that shortly the switches 141 and 148 will open to break the oil valve circuit. Thereafter, with the lock-out circuits 183, 91, 189 closed, the mechanism will proceed to lock-out.

If power fails with the switch 50 stuck closed, after ignition has occurred, upon restoration the mechanism will cycle out to starting period, since the switch is out of circuit by opening of the switch 184. Thereafter, as above, no new cycle can start.

If power fails after ignition with the relay switches 186 stuck in hot position, upon its restoration the mechanism will cycle as long as the switch 119 is closed, and when that switch is open the burner motor will operate without oil.

If power fails during the starting period and the relay switch 180 sticks closed, upon its restoration, the mechanism will resume its cycle, and reach either the running period or the lock-out, depending on ignition. And, if a running period occurs, it will nevertheless be followed by a lock-out, as above.

If the relay 180 sticks in lock-out position, upon manual reset, the switch 149 will be shunted, and by recycling immediately upon closing of the room thermostat, the mechanism will cycle to a running period, if ignition occurs, and ultimately to a relock-out whether or not ignition occurs.

By virtue of deenergizing the relay 186 at the end of a running period, rendering the position of the switch 50 inconsequential so far as running out the scavenging period is concerned, that period is not interrupted by any pause to cool the stack unit, which may use the entire scavenging time for that purpose. However, recycle cannot start until the unit cools, because if the instituting circuit is closed with the unit hot enough to close the switch 50, the relay 186 will instantly

open the switch 189, and prevent operation of the control motor, until the unit does cool. The device will be held only in starting position. However, for the unit to require any such time for cooling is grossly abnormal for the present stack unit.

If the room thermostat opens and quickly recloses during a running period, the relay 180 will nevertheless open the switch 184 and begin 10 a scavenging period. If the relay 180 switches stick, or fail closed, and the room thermostat recloses prior to cooling of the switch 50, and prior to flame failure, the running period will continue. If flame failure has occurred, the 15 switch 50 will very shortly open, and a lock-out circuit will be established.

If the room thermostat fails closed during a running period, the mechanism will run on the limit switch L (see Fig. 40). When the limit 20 switch once opens, it deenergizes the relay coils, and opens their switches. Its location permits the mechanism to continue the scavenging cycle, and to restart after cooling of the limit switch. In fact, whenever the burner runs on the limit 25 switch, it will do so only once for each cycle. If the limit switch remains hot at the beginning of a subsequent cycle, upon opening of the instituting circuit switch 146, and the simultaneous closing of the scavenging switch 146, the mechanism 30 will cycle through the scavenging operation and return to starting position.

If the limit switch be located at 12 (Fig. 40), the relays will open when it does, but continued cycling will await cooling of the limit switch, 35 whereupon the mechanism will cycle out through the scavenging period and restart.

Of course, the normal operation of the limit switch, with the thermostat closed, is substantially the same as above.

40 The length of the cycle may be varied as may be the individual durations of the several phases providing only that the cycle itself be not changed. Widening or narrowing the cycle is a matter of changing the ratio of the gears 81 and 45 83. The mechanism can be used with any kind of fuel to be ignited, such as gas. The oil supply control may be merged into the burner motor, or the burner motor may be merged into the oil supply mechanism, at the sacrifice of certain obvious advantages of the present arrangement. 50 It is not essential that there be an igniter in the cycle, because it will have value where other ignition means, such as a pilot light, is used.

55

Operation of Fig. 41

With the connections as in Fig. 41, the igniter cannot operate until the circuit through the oil valve switch 147 is completed. This occurs after 60 30 seconds. The switch 93 closes no later than the switch 147.

When the switch 203 is open, the igniter will start with the oil, at 30 seconds. When the running period begins, after 120 seconds, the igniter stops. When the switch 203 is closed, continuous ignition occurs throughout the running period.

With the igniter connected through the oil supply circuit, even crossing the leads from the 70 igniter and oil supply will not create a hazardous condition. If the oil supply be connected to terminal 64, and the igniter to the terminal 62, the result will only be that oil will stop upon establishment of a running period, and there will result a failure of ignition, followed by scavenging 75

out and recycling. No danger inheres in this operation.

What is claimed is:

1. In a mechanism of the kind described for use with a flame producing means, a control device for effecting sequential operations from a starting position, a first and a second circuit therefor, said control device being constructed to control a running period for the flame producing means, said first circuit being constructed after beginning of the running period to cause the control device to operate through a cycle to starting position, and the second circuit being constructed to cause the control motor to operate after beginning of the running period to a position of inoperation short of starting position, and means responsive to existence of the flame to select which circuit is effective, and means dependent upon the control device's being in starting position for instituting operation of the same.

2. In a mechanism of the kind described for use with a burner device, a fuel supply means therefor, an ignition means therefor, and a space thermostat responsive to the heat produced thereby, the combination of a control device for effecting sequential operations, means operable under control of the control device to cause operation of the fuel supply means upon closing of the thermostat, means under control of the control device for effecting operation of the ignition means, means including the control device for holding the fuel supply means and ignition means in operation for a predetermined period independently of the thermostat, means including the control device for returning the fuel supply means to control by the thermostat after the period, a means including the control device operated upon opening of the thermostat to hold the fuel supply means inoperative for a period after opening of the thermostat, and means to lock the mechanism out at the end of said last-named period upon failure of ignition to be effective at the time the burner device is returned to control by the thermostat.

3. In a mechanism of the kind described for use with a burner, a pair of power operated relays, a control device to effect sequential operations, a thermostat, a burner device for producing predetermined flame conditions at the burner, means responsive to flame conditions produced by the burner device to control the second relay, means including the control device and the first relay to start operation of the burner device, means under control of the control device to cause operation of itself and to maintain the burner device for predetermined, limited intervals, regardless of the operating position of the first or second relay, and means operated by the second relay adapted to stop operation of the control device after one such interval when the flame conditions at the burner are at the predetermined condition.

4. In a mechanism of the kind described, a control device for effecting sequential operation, a fuel supply device, an air supply means, an ignition means, and a fuel pre-heating device, a space thermostat, means including the thermostat and the control device for causing the control device and the air supply device to begin operation, means for holding said operation after it starts independently of the thermostat, said control device being adapted to cause operation of the ignition device, and means thereafter operable by the control device to cause operation of the fuel supply means, whereby ignition may occur, means

including the control device for effecting operation of the fuel pre-heating device, said pre-heating device being adapted to prevent operation of the control device until the fuel attains a desired temperature, a switch means operated upon existence of flame, and adapted to render the control device inoperative, means including the control device for rendering the mechanism subject to control of the thermostat when ignition occurs, said means including means to hold the air supply device in operation as well as means to hold the fuel device in operation, means operated upon change of the thermostat to shut off the fuel supply means and to restart the control device, and means including the control device to continue operation of the air supply device for a period after the flame has ceased to exist.

5. In a mechanism of the kind described for use with a burner mechanism, a control device 20 providing a plurality of operations of the burner mechanism, an instituting circuit for causing starting of the control device into operation, circuit means including a self-holding relay and circuit for holding the control device in operation 25 independently of the instituting circuit, circuits controlled by said control device establishing a starting interval to cause ignition of the burner mechanism, and a running interval during which combustion exists, and means to open the instituting circuit prior to the end of the starting interval, and said relay being adapted to control said circuits providing the starting and running intervals after said instituting circuit opens, and means operated upon release of the relay during 35 either the starting or the running interval to prevent unlimited operation of the burner mechanism.

6. In a mechanism of the kind described, a burner mechanism, a control for the burner mechanism comprising a space thermostatic means to control the operation thereof, said means being movable to an operative position in response to demand for heat from the burner, means including a circuit adapted to be established through 40 said thermostatic means in operative position to effect a running period of operation of the burner mechanism, means providing an operation after the running period to return the control to starting position, and means to cause the last-named means to function even if the thermostatic means remains in operative position, together with means preventing recycling by the control until the thermostatic means leaves its operative position.

55 7. In a mechanism of the kind described, a fuel supply device, a space thermostatic means operable in response to demand for heat in the space, a relay controlled by said means in turn to control the operation of the fuel supply device, said relay having a switch movable to operating position, means to effect a cycling operation of the fuel supply device, comprising circuit means providing a running period of operation for the fuel supply device, through the relay switch in operating position, means providing a cycling operation after the running period, means to prevent operation of the fuel supply device if the relay switch sticks in operating position after a running period, and means to prevent the cycling means from operating when the relay switch sticks.

60 8. In a mechanism of the kind described for use with a burner mechanism including fuel supplying means, and a space thermostat, the combination of a relay switch adapted to be connected

for operation upon movement of the thermostat to its operative position, for controlling operation of the burner mechanism, means adapted to include the thermostat in operating position for starting the burner mechanism, means including the relay in operating position for maintaining the fuel supplying means in operation and providing a running period for the burner mechanism, and means to prevent supply of fuel after a running period if the relay switch sticks in operating position. 10

9. In a mechanism of the kind described, a burner mechanism, a cycling control including means providing a running period therefor, means providing a scavenging period therefor after the running period, means providing a lock-out adapted to follow the scavenging period, said running period means comprising burner mechanism energizing means, including a control switch operable to running position, said energizing means being rendered effective by operation of the control switch into running position, and means causing the lock-out means to be effective if the control switch sticks in running position after a running period. 15

10. In a mechanism of the kind described, a burner mechanism, cycling control means including a thermostat subject to fortuitous displacement, switches in said control means operated by the thermostat on closing thereof, said switches being adapted to be opened if the thermostat opens, means including the thermostat in cold position and said switches closed upon closing of the thermostat to provide a running period for the burner mechanism, and means to prevent reoperation of the burner mechanism if the thermostat is opened during the running period but the switches stick closed. 20

11. In a mechanism of the kind described for use with a fuel supply device, a cycling control therefor including a motor and a plurality of sequentially operated switches operated thereby, said control being adapted to establish a circuit for the device including certain of said switches to provide a starting period of operation of the device during which combustion may occur, a second circuit for the device including other of said switches to provide a second period during which combustion may continue, means in the control to maintain the device inoperative for a third period after the second period, said last-named means being adapted to return the control to starting position at the end of the third period, from which it may recycle, means in the control to prevent recycling of the control and to lock-out the device after at least a substantial part of the third period, and automatic means responsive to existence of combustion, operative at the end of the starting period to determine whether or not the lock-out means shall be actuated to prevent such recycling. 25

12. In a mechanism of the kind described for use with a fuel supply means, a cycling timing control adapted to provide sequential operations for the fuel supply means, means to energize the timing control, means under control of the timing control to maintain the fuel supply means in operation for a first period during which combustion may occur, means to maintain the fuel supply means inoperative for a period after combustion has stopped, said last-named means being adapted to return the control to starting position after the inoperative period, for recycling, means independent of the total time of operation of the timing control to cause the fuel sup- 30

ply means to lock-out after at least a substantial part of the inoperative period has passed, and means responsive to existence of combustion at the end of the first period to render the lock-out means ineffective to prevent recycling of the control. 5

13. In a mechanism of the kind described, a fuel supply means, a cycling timing control to provide sequential operations for the fuel supply means, means to energize the timing control, means under control of the timing control to maintain the fuel supply means in operation for a first period during which combustion may occur, a space thermostat, a combustion-responsive thermostat, said control being adapted to render operation of said fuel supply means subject to said space thermostat and combustion thermostat for a second period, means to restart the timing control for a third period after said space thermostat is satisfied, said timing control having means thereafter to maintain the fuel supply means inoperative for a fourth period during which scavenging may occur, means to lock-out the fuel supply means after at least a substantial part of the fourth period, and means under control of the combustion thermostat to render the lock-out means ineffective to prevent recycling if combustion exists at the end of the first period. 10

14. In a mechanism of the kind described, a fuel supply means, a cycling timing control, means to effect actuation of the timing control, combustion-responsive means, means under control of the timing control to render the fuel supply means operative during a first period during which combustion may occur, a first and a second circuit for maintaining actuation of the timing control during a scavenging period after the first period, a switch in the first circuit maintained closed by the timing control for a fuel scavenging period to the end of the cycle, a switch in the second circuit maintained closed by the timing control for a period less than the fuel scavenging period, means operated by the combustion-responsive means upon existence of combustion to select the first circuit, and upon lack of combustion to select the second circuit, and means to render the timing control actuation effecting means ineffective to recycle the control upon opening of the second circuit switch. 20

15. In a mechanism of the kind described, a fuel supply means, a cycling timing control adapted to provide sequential operations of the fuel supply means, said timing control including means to render the fuel supply means operative during a starting period during which combustion may occur, and means to maintain itself operative and the fuel supply means inoperative during a scavenging period after the starting period, said timing control also including means to stop itself and lock-out at a point between the start and the finish of the scavenging period, means responsive to lack of combustion at the end of the starting period to render the lock-out means effective, and means to effect operation of the timing control, said means being ineffective to effect such operation at the point of locking-out, but being adapted to be effective at the end of a fuel scavenging period. 30

16. In a mechanism of the kind described, a fuel supply means, combustion-responsive means including relay switch means operated in response to existence of combustion, temperature-responsive means including relay switch means operated in response to existence of predetermined temperature conditions, a cycling control motor, and 35

switch means operated thereby, means including both relay switch means in operative positions, and a cycling motor switch to hold the fuel supply means in operation, and means to restart the cycling motor upon release of the combustion relay switch to stop the fuel supply means if the temperature relay switch means fails in operative position.

17. In a mechanism of the kind described, a fuel supply means, a timing control therefor, a space thermostat and switch means operated under control thereof, means including the space thermostat switch in cold position of the thermostat to effect operation of the timing control, said timing control including means to effect operation of the fuel supply means for a starting period independent of the space thermostat, and means to render the fuel supply means subject to the thermostat switch in cold position for continued operation thereafter, means to reoperate the timing control upon movement of the thermostat switch to hot position, said timing control being adapted to continue such reoperation for a further period during which it maintains the fuel supply means inoperative, and means to cause said timing control to operate for said further period even after the thermostat switch fails in the hot position of the thermostat.

18. In a mechanism of the kind described, a fuel supply means, a timing control therefor, a space thermostat and switch means operated under control thereof, means including the space thermostat switch in cold position to effect operation of the timing control, said timing control including means to effect operation of the fuel supply means for a starting period independent of the space thermostat, and means to render the fuel supply means subject to the thermostat switch in cold position for continued operation thereafter, means to reoperate the timing control upon movement of the thermostat switch to hot position, said timing control being adapted to continue such reoperation for a further period during which it maintains the fuel supply means inoperative, means to cause said timing control to operate for said further period even after the thermostat switch means fails in the hot position of the thermostat, said last means including a limit switch, and means to effect said reoperation of the timing control for said further period immediately upon operation of the limit switch.

19. In a mechanism of the kind described for use with a fuel supply means, a timing control therefor, means to effect actuation of the timing control, said control being adapted to effect operation of the fuel supply means for a starting period during which combustion may occur, and being adapted to effect a running period during which operation of the fuel supply means may continue, and said control having means to provide a period during which the fuel supply means is deenergized, and means to effectuate operation of said control to produce said last-named period whenever during the starting or running period, after the fuel supply means has started operation, the fuel supply means is deenergized, prior to its being reenergized again.

20. In a mechanism of the kind described for use with a fuel supply means, a timing control, means to effect operation of the timing control, said control being adapted to effect operation of the fuel supply means for a starting period during which combustion may occur, and being adapted to effect a running period during which operation of the fuel supply means may continue,

said control having means to provide a period during which the fuel supply means is held inoperative, means responsive to failure of power to render the fuel supply means inoperative at any time after it has begun operation during the starting or the running period, and said last-named means being adapted to render the inoperative period means effective upon restoration of power to insure a scavenging period before the fuel supply means may again become operative.

21. In a mechanism of the kind described, a fuel supply means, a cycling timing control, means to effect operation of the timing control, 15 said timing control having switch means operated sequentially, a first circuit for the timing control including a first switch operated by the timing control to cause said circuit to cycle the timing control back to starting position, a second circuit for the timing control including a second switch operated by the timing control to cause said circuit to cycle the timing control to cycle to a position short of the starting position, means operated by the timing control to operate the fuel supply means for a starting period beginning after closure of the first and second switches and stopping prior to opening of the second, means operated by the timing control for enabling the fuel supply means to continue 20 in operation for a running period after the starting period, said enabling means being adapted to render the timing control inoperative for said running period, means including a combustion-responsive means operative upon existence of 25 combustion to maintain the fuel supply means operative during the running period, and means under control of the combustion-responsive means to select the first circuit to the timing device if combustion fails and the combustion-responsive means becomes inoperative during the 30 running period, and to select the second circuit to the timing device if combustion fails at the end of the starting period, and said means to effect starting of the timing control being dependent upon cycling of the timing control back 35 to its starting position.

22. In a mechanism of the kind described, a fuel supply means, air supply means, and a timing control adapted to produce a cycle of operations of said means and return to starting position, means to start the timing control dependent upon its being in starting position, said control including means to operate both the fuel and air means for a starting period during which combustion may occur, and including means responsive to lack of combustion at the end of the starting period to maintain the fuel supply means inoperative for a period thereafter with means to maintain the air device operative during said period of inoperativeness of the fuel device, and said control including means thereafter adapted to stop the air supply means and control short of starting position.

23. In a mechanism of the kind described for use with a burner device, a control device for effecting sequential operations of the burner device including a running period, a first and a second circuit for the control device, said control device having circuit closing means operable to open the two circuits at different times to cause the control device to stop at different times, said control device being adapted to operate the circuit closing means in both circuits during the running period, means to maintain one circuit open during the running period and to close it

thereafter, means responsive to existence of power to select said one circuit, and responsive to failure of power to select the other circuit, whereby upon existence of power the control device may operate after the running period for a first interval, and upon failure of power and subsequent restoration it may operate for a different interval, and means to render the control device incapable of restarting when it has operated for said second interval.

24. In a mechanism of the kind described, a burner, means for supplying a combustion ingredient to the burner, a cycling control device having first means to maintain the supplying means in operation for a period until the control device returns to starting position, and having a second means to maintain the supplying means in operation for a period short of return of the control device to starting position, means operated by the control device to stop the control device prior to the end of either period, means to maintain the supplying means in operation during said stoppage, means operable upon combustion at the burner to select the first means aforesaid, and operable upon lack of combustion at the outset of the period of stoppage to select the second means aforesaid, and means dependent upon having the control device in its starting position to effect a restart of the same.

25. In a mechanism of the kind described for use with a burner mechanism under control of a space thermostat and including fuel supplying means, a relay switch controlled by the space thermostat for controlling operation of the burner mechanism, means including the thermostat in operating position for starting the burner mechanism, means including the thermostat in operating position for maintaining the fuel supply means in operation and providing a running period for the burner mechanism, means to prevent supply of fuel after a running period if the relay switch sticks in operating position, said means comprising a second relay having switches controlling the burner mechanism, and a coil dependent upon the thermostat in its operative position to operate the said switches into position to maintain operation of the burner mechanism.

26. In a mechanism of the kind described for use with a burner mechanism under control of a space thermostat and including fuel supplying means, a relay switch controlled thereby for controlling operation of the burner mechanism, means including the thermostat in operating position for starting the burner mechanism, means including the thermostat in operating position for maintaining the fuel supplying means in operation and providing a running period for the burner mechanism, means to prevent supply of fuel after a running period if the relay switch sticks in operating position, said means comprising a second relay having switches controlling the burner mechanism, and a coil dependent upon thermostat in its operative position to operate the said switches into position to maintain operation of the burner mechanism, together with means dependent upon existence of combustion to maintain the coil energized.

27. In a mechanism of the kind described for use with a fuel supply means under control of a space thermostat, a cycling control device including a control motor and switch means cyclically operated thereby, a circuit for the motor, a relay under control of the space thermostat including a coil, and a switch means operated thereby to

close the motor circuit, a circuit for the fuel supply means dependent upon operation of the space thermostat relay by movement of the said thermostat to cold position, a combustion-responsive relay and a switch means operated thereby, said last-named switch means including a switch arranged to control operation of the circuit for the fuel supply means, the space thermostat being also in series with the coils of said relays whereby if it opens, said fuel supply means is immediately deenergized even if one of said relay switches fails in closed position, and said circuit for the fuel supply means being also controlled by the control motor switch means.

15 28. In a mechanism of the kind described for use with a fuel supply device, a relay, a cycling control device, a pair of circuits for the control device, a relay switch adapted to select the first circuit when energized and the second when de-20 energized, a switch operated by the control device in one circuit to stop it in a locking position preventing operation of the control device, a switch operated by the control device for stopping it after return of the control device to starting position, 25 a circuit through the relay in its locking circuit position for energizing the fuel supply device, a switch operated by the control device to open the fuel supply device prior to opening of either control device circuit, and a thermostatic means controlling energization of said relay.

29. In a mechanism of the kind described for use with a burner, a fuel supply means, and an igniter for the burner, the combination of control means to provide operation of the fuel supply 35 means for a starting and a running period, circuit means under control of the control means to effect initiation of operation of the igniter during the starting period, switch means to render the igniter operative during the running period, said 40 last-named switch means being selectively operative independently of the control means, and means to render the igniter inoperative after the running period regardless of the circuit means and the switch means.

45 30. In a mechanism of the kind described for use with a fuel supply means under control of a space thermostat and a combustion thermostat, a control motor having switch means to effect a cycle having a starting period and a running 50 period for the fuel supply means, and to reestablish starting conditions after the running period, a pair of relay coils, both adapted for disposal in series with the space thermostat and one in series with the combustion thermostat, a switch 55 operated by each coil, an energizing circuit for the coils being provided through a switch of each coil closed by energization thereof, and adapted to include the space thermostat, and a running period circuit for the fuel supply means being 60 provided through both said coil switches, and a circuit for the control motor including a switch held open upon energization of the second coil, whereby when either thermostat opens the fuel supply means will be deenergized and the control 65 motor circuit will be rendered subject to reenergization.

31. In an apparatus of the kind described for use with a burner and means to supply fuel to the burner, a control mechanism for controlling the 70 fuel supply means, said control mechanism including means adapted to provide a cycle of operation for the burner including starting, running, scavenging, and lock-out thereof, followed by a return to starting position, and comprising 75 means adapted to put the fuel supply means in

operation, for a starting period, means to maintain the fuel-supply means in operation after the starting period for a running period, means to provide a period of inoperativeness of the fuel supply means after the running period for a scavenging period, means to cause at least a part of the scavenging period to occur after any starting period, and then to cause a lock-out of the fuel supply means prior to return of the control to starting position during any cycle, upon absence of combustion at the end of the starting period.

32. In a mechanism of the kind described, for use with a burner, a fuel supply device and an air supply device for the burner, the combination of a power failure circuit holding device, a pair of switches operated by said holding device, a control motor, means to operate the circuit holding device upon existence of a predetermined condition, circuit means including one of said switches operated upon energization of the circuit holding device to cause actuation of the control motor, means to cause operation of the air supply device upon operation of the control motor, means including the other of said switches to cause operation of the air supply device upon deenergization of the circuit holding device, and circuit means dependent upon energization of said one switch for energization of the fuel supply means.

33. In a mechanism of the kind described, for use with a fuel supply device, a control motor for controlling operation of the fuel supply device, and a power failure relay, with circuit means for effecting operation of the control motor when the power failure relay is either energized or deenergized, and circuit means controlled by the control motor and arranged to operate the fuel supply device only when the relay is energized.

34. In a mechanism of the kind described for use with a burner means requiring a first and a second combustion ingredient, the first being air and the second being fuel, and an ignition means, the combination of a control device, said control device including means adapted to maintain itself, both combustion ingredient supply means and the ignition means in operation for a starting period, and said control including means adapted to cause the two combustion ingredient means to operate for a running period, the control device including means responsive to the successful production of flame in the starting period to cause the first combustion ingredient means to operate after the running period and to render the other inoperative, through a scavenging period until the control returns to starting condition for a recycling, and said control including means operated upon failure to produce flame by the end of the starting period to cause the first combustion ingredient means to operate for a portion of said scavenging period, and then to stop in a position preventing recycling, and said control device also including means operated upon flame failure as aforesaid to render the second combustion ingredient means inoperative.

35. In a mechanism of the kind described for use with a burner mechanism, a combustion-responsive device operable upon existence of com-

10 bustion at the burner mechanism, and an external control device operable to demand or deny heat need from the burner mechanism, the combination of a timing control device having means to provide a starting period for the burner mechanism in response to demand for heat by the external control device, means to provide a scavenging period during which the control mechanism maintains the burner mechanism inoperative after the starting period, means adapted for connection with the combustion-responsive device for holding the burner mechanism in operation after the starting period and before the scavenging period, and means in the control device to lock-out the burner mechanism and hold the same against any operation, said means being rendered effective upon failure of combustion at the end of the starting period, to effect said lock-out after the beginning of the scavenging period.

15 36. In a mechanism of the kind described for use with a burner having a fuel ingredient supply device and an air supply device, the combination of a power operated relay switch mechanism, a control device for effecting sequential operations of itself, the air supply device and the fuel ingredient supply device, to produce combustion at the burner and to maintain the same, means to operate the air supply device including 20 both the relay switch mechanism and the control device, and means including the control device for operating the air supply device and the control device whatever the condition of the relay mechanism.

30 37. In a mechanism of the kind described, a control device for effecting sequential operations including a plurality of switches and means for closing them in a predetermined order to effect a cycle and to return thereafter to starting position, means dependent upon return to starting 40 position to restart the control device, mechanism to be operated under control of the control device, means causing the control device to become ineffective to complete the cycle for the operated mechanism, and manually movable means movable to effect mechanical engagement with the closing means, and further manually movable to bodily displace the same and such of the switches as to reestablish the starting position.

45 38. In a control for use with a fuel burner including means to supply fuel, under control of a space thermostat and a combustion thermostat operated to circuit closing position upon existence of combustion, means responsive to demand by the space thermostat to cause the fuel supply means to supply fuel to be ignited, a flame-responsive relay including a coil in series with the space thermostat and the combustion thermostat, and energized upon demand for heat by the space thermostat and closure of the combustion thermostat in response to existence of combustion, relay switch means closed by said coil upon energization thereof, a circuit including said relay switch means to operate the fuel supply means when said coil is energized, and means to prevent the fuel supply means from supplying fuel after the space thermostat stops demanding heat but the relay switch fails in circuit closing position.

GEORGE D. BOWER.
